SANDING MACHINE

William L. Petersen, Muskegon, Mich., assignor
to Clarke Sanding Machine Company, Muske-
gon, Mich., a corporation of Michigan

Application May 27, 1953, Serial No. 25,209
Term of patent 14 years

(Cl. D9—2)

To all whom it may concern:

Be it known that I, William L. Petersen, of Muskegon, Michigan, have invented a new, original, and ornamental Design for a Sanding Machine, of which the following is a specification, reference being had to the accompanying drawing, forming a part hereof.

Figure 1 is a front perspective view of a sanding machine, showing my new design;

Figure 2 is a side elevational view thereof.

The opposite side of the machine is the same as shown in Figure 2 and the rear surface is substantially plain. The dominant features of the

design are illustrated in full line in the drawings.

I claim:

The ornamental design for a sanding machine, as shown and described.

WILLIAM L. PETERSEN.
